UNITED STATES PATENT OFFICE.

WILLIAM LUTHER BOGLE, OF BENTOAK, MISSISSIPPI, ASSIGNOR OF ONE-HALF TO W. C. MCCLURE AND ONE-HALF TO JAMES THOMAS HARRISON, OF COLUMBUS, MISSISSIPPI.

WASHTUB.

No. 898,087.

Specification of Letters Patent.

Patented Sept. 8, 1908.

Application filed September 28, 1906. Serial No. 336,568.

To all whom it may concern:

Be it known that I, WILLIAM LUTHER BOGLE, a resident of Bentoak, in the county of Lowndes and State of Mississippi, have invented certain new and useful Improvements in Washtubs; and I do hereby declare the following to be a full, clear, and exact description of the invention, such as will enable others skilled in the art to which it appertains to make and use the same.

My invention relates to improvements in wash tubs, an object of the invention being to provide a tub made of sheet metal having permanent or removable corrugated sheet metal wash boards located at inclined portions of the tub walls to facilitate the washing of goods, said tub being manufactured at comparatively small cost and strong and durable in use.

20 A further object is to provide a wash tub having inclined ends and made with wash boards at one or both of said inclined ends.

With these and other objects in view, the invention consists in certain novel features 25 of construction and combinations and arrangements of parts as will be more fully hereinafter described and pointed out in the claims.

In the accompanying drawings, Figure 1 30 is a perspective view illustrating my improvements. Fig. 2 is a view in longitudinal section thereof. Fig. 3 is a view illustrating a blank from which the tub can be formed.

1 represents the tub proper, the form of 35 tub shown in Fig. 1 being made from a blank such as illustrated in Fig. 3, or if desired, the tub may be stamped or drawn from a single plate without seams. The blank, shown in Fig. 3, comprises a central body portion, which constitutes the tub bottom when the blank is folded, and from this body portion, end wings 4 and side wings 5 project. The side wings 5 having inclined or tapering ends, so that when the ends 4 are folded 40 45 thereagainst and secured by seaming or otherwise, the ends will be disposed at an angle or incline. Wash boards, composed of corrugated metal plates, and illustrated at 6, are secured to the ends by rivets 7. The up-

per ends of the wash boards 6 are bent over 50 the edges of the tub ends and bent into the form of handles 8 to facilitate the moving of the tub. Fixed wash boards are therefore provided at the ends of the tub and located in just the proper position or incline to permit 55 the best of work and by providing wash boards at both ends of the tub, two persons may work at the same tub at the same time. The tub is also a very desirable shape when used for bathing purposes as such tubs are 60 often used in rural districts. The wash boards may be variously corrugated and shaped according to the work to be done and for convenience the wash board at one end of the tub may be made with smaller corrugations 65 than the other and various other modifications may be made in the wash boards to best perform the work intended.

I do not restrict myself to any particular shape of tub, nor to the manner of making 70 the same, nor to the form of wash board or manner of securing the same, but consider myself at liberty to make such slight changes and alterations as fairly fall within the spirit and scope of my invention as defined by the 75 appended claims.

Having fully described my invention, what I claim as new and desire to secure by Letters-Patent, is:—

1. A wash tub composed of sheet metal 80 and having an inclined wall, said inclined wall provided with a wash board permanently riveted thereto, and having a portion extending beyond the tub and forming a handle..

2. A wash tub comprising a metal body 85 having inclined ends, a corrugated metal wash board permanently fixed to each inclined end of the metal body, and the upper ends of said wash boards having portions bent forming handles for the tub. 90

In testimony whereof, I have signed this specification in the presence of two subscribing witnesses.

WILLIAM LUTHER BOGLE.
